United States Patent Office.

HENRY SIDLE, OF MINNEAPOLIS, MINNESOTA.

Letters Patent No. 67,597, dated August 6, 1867.

IMPROVED WASHING MACHINE.

The Schedule referred to in these Letters Patent and making part of the same.

TO ALL WHOM IT MAY CONCERN:

Be it known that I, HENRY SIDLE, of Minneapolis, in the county of Hennepin, and in the State of Minnesota, have invented certain new and useful Improvements in Washing Machines; and do hereby declare that the following is a full, clear, and exact description thereof, reference being had to the accompanying drawings, and to the letters of reference marked thereon.

In the annexed drawings, making part of this specification, A represents the body of the machine, which consists of a square box supported upon suitable legs, and provided with a hinged cover, A'. B represents a vertical shaft, which is provided with a series of arms, C C, which pass through said shaft at an angle less than a right angle. The shaft B is provided also, upon its upper end, with a bevel gear-wheel, D, which said wheel has a hub which tapers off from both faces of the wheel. J represents a metallic plate which is secured upon the box-cover A', and through which the shaft B passes. The hub, on the under side of the wheel D, rests; having its bearing upon this plate. H and G represent two arched frames cast of metal, both alike, except that the frame H has a brace or bar, I, cast across it, in which is formed an opening to receive the upper end of the shaft through bevel-wheel D. The two frames H and G are secured a little distance apart upon the cover A. E represents a bevel-wheel, the shaft of which has its bearing in openings in the frames G and H, which are cast for that purpose. Wheel E is provided with a handle, F, and gears into the bevel-wheel D. By working the handle F the wheel E is partially rotated backwards and forwards, giving a backward and forward rotary motion to the bevel D, with its shaft B, washing the clothes in box A by agitation.

I claim the shaft B, provided with its angular arms C C and bevelled cog-wheel D, and operated by means of the wheel E between frames G and H, with its handle F, in the manner and for the purposes set forth.

In testimony that I claim the foregoing, I have hereunto set my hand this 30th day of May, 1867.

HENRY SIDLE.
